UNITED STATES PATENT OFFICE.

EMIL WISCHOW, OF LUEBECK, GERMANY.

HEWING APPARATUS FOR OPEN-AIR MINING.

No. 919,105.

Specification of Letters Patent.

Patented April 20, 1909.

Application filed March 12, 1908. Serial No. 420,751.

To all whom it may concern:

Be it known that I, EMIL WISCHOW, a citizen of the German Empire, residing at Luebeck, in the State of Luebeck and German Empire, have invented Improvements in Hewing Apparatus for Open-Air Mining, of which the following is a specification.

This invention relates to hewing apparatus for the mining of minerals, especially of brown coal, which are to be worked in open-air workings.

The essential novelty in the invention is the employment of a carriage or slide running along the working-face on a rigid guide-rail which carriage or slide supports the cutting tools for hewing down the materials.

The invention can be carried out in a great variety of ways. The drawings show some of the most important and preferable forms of the apparatus.

Figure 1 shows a side view of a hewing apparatus constructed in accordance with the invention. Fig. 2 shows the tool-slide for the same drawn to a larger scale. Fig. 3 shows a modification of the upper part of the apparatus shown in Fig. 1. Fig. 4 is a side view of another hewing apparatus, the lower part of which is shown in front view in Fig. 5, and in plan in Fig. 6, while the upper part is shown in plan in Fig. 7 and in back view in Fig. 8. Figs. 9 and 10 show respectively a front and side view of a special form of the cutting tool. Fig. 11 shows the arrangement of several such cutting tools in one tool-slide. Figs. 12 and 13 show a side view and plan respectively of a tool-slide with rotating upper part. Fig. 14 shows a hewing apparatus with an adjustable tool, and Figs. 15 and 16 show, to a larger scale, a side view and plan respectively of a tool-slide with an adjustable tool.

The arrangement illustrated in Figs. 1 and 2 shows two carriages, one of which, 1, moves on rails 3 at the lower part of the working face to be hewn down, the other, 2, on rails 4 at the top of the working face and both parallel to the latter. The carriage 1 supports a framing, to the corner point 5 of which is hinged a link 6. The carriage 2 likewise supports a framing to which is hinged, at the point 7, a link 8. The links 6 and 8 carry the rigid guide-rail 9 for the slide 10. The rigid guide-rail 9 consists of a lattice-girder the length of which is somewhat greater than the height of the working face to be hewn down, and is provided with

guides, or the like, for the slide 10. The rigid guide-rail 9 is raised and lowered by the two rope or chain tackles 11 and 12 its ends swinging around the points 5 and 7 by means of the two links 6 and 8. These two links 6 and 8 are of equal length, in consequence of which the guide-rail 9 is guided parallel to itself, that is to say, it remains always parallel to its original position. In Fig. 1 the two extreme positions of the rigid guide-rail 9 are shown, the lower extreme position being shown in full lines, the upper in dotted lines. When the guide-rail 9 is of great length it is held by two sliding supports 13 and 14 which are hinged to the framing of the carriages 1 and 2, and grasp the guide-rail 9 at the side turned away from the working face, by means of sliding shoes 15 and 16. The slide 10 guided on the rigid guide-rail carries, by means of rollers 17 and 18, a chain or band 19 furnished with picks or cutters. This consists of one or more endless chains carried side by side around the rollers 17 and 18, which chains are provided at regular intervals with cutters 20. An electric motor 21, or other suitable engine, turns the roller 18. The slide 10 is fixed to an endless rope 22 which is led over rollers 23 and 24 at the ends of the guide-rail 9 and can be moved by a windlass placed on the carriage 2. By means of this rope the slide 10 is moved up and down at pleasure on the guide-rail 9.

On the lower carriage 1 is arranged a bucket-chain 25 which runs over three sprocket wheels 26, 27, and 28. The front sprocket 28 is placed at the connecting point of the link 6 with the rigid guide-rail 9. The bucket-chain consequently adapts itself to every movement of the lower end of the guide-rail 9. Each bucket of the bucket-chain is furnished with a cutter so that it can take away, when the bucket-chain revolves, the hewn-down material. The link 6 forms at the same time the bucket-guide for the front part of the bucket-chain. The rear sprocket-wheel 26 of the bucket-chain is driven by any suitable motor. The buckets of the bucket-chain 25 empty themselves, in passing over the rear sprocket 26, and pour their contents on to an inclined plane 29 which delivers them to a traveling band 30 connected to the carriage 1 by means of a carrier 31. This traveling band 30 throws its contents into a hopper 32 movable to and fro on the carrier 31, not wholly shown in the drawings, from which hopper the ma-

terials fall into the wagon 33 of a transport-railway 34 which conveys the material to the place where it is to be operated upon, or to the store.

5 The above described apparatus operates as follows:—Assuming that the carriages 1 and 2 with the whole apparatus are standing at the end of the working face which is to be hewn down, and the guide-rail 9 in the position shown in dotted lines in Fig. 1. The slide 10 stands at the top of the upper edge of the working face to be hewn down. The cutter-chain 19 is set in motion by its motor 21 and the bucket-chain by its motor. In this 10 position of matters the cutter 20 of the cutter chain 19 may penetrate to a certain depth into the working face to be hewn down, which depth is dependent upon the nature of the materials to be operated upon. The 15 slide 10 is now moved downward on the guide-rail 9 and the material that stands opposite the cutters 20 is loosened thereby. The loosened material falls down the working face and is received by the buckets of the 20 bucket-chain 25. When the slide 10 has reached the lower end of the guide-rail 9 it will have hewn down a strip of the working face corresponding to the working width of the cutter-chain 19 and of the whole height 25 of the working face. Then the carriages 1 and 2 are simultaneously pushed forward a distance equal to the width of the cut just made, while the cutter-chain 19 and bucket-chain 25 continue to work and loosen the 30 material opposite to them. The slide 10 is now again drawn up to the upper edge of the working face while it continues to hew down the material in front of it. When the slide 10 has again reached the top of the working 35 face the carriages 1 and 2 are again pushed forward by the width of a cut, and the slide 10 is again moved downward. The process is continued until the whole working face has been hewn down to the depth of the cut. 40 The guide-rail 9 is then lowered by slackening out the tackles 11 and 12 so far that the cutter-chain 19 and the bucket-chain 25 can penetrate afresh to a definite depth into the working face, and the above described movements of the apparatus are repeated. As the 45 bucket-chain 25 reaches close up to the lower end of the rigid guide-rail 9 it hews out mechanically the part of the working face at the foot of the apparatus, which has not been 50 reached by the cutter-chain.

When the rigid guide-rail 9 reaches the position shown in full lines in Fig. 1 it is, after completion of its last proposed cut, drawn up into its highest position, and the rails 3 and 4 55 are, with the entire apparatus, moved so far forward that the cutter-chain 19 comes again close to the working face. The above described operation is then recommenced. But the revolving cutters and their guidance 60 on a rigid guide-rail allows of the apparatus

hewing each separate part of the working face instead of working the whole thereof uniformly. If, for example, there occurs in the brown coal to be won a horizontal seam of loam or the like, the slide 10 may be 70 clamped to the guide-rail 9 at the height of the seam of loam and then by moving the carriages 1 and 2 on their rails 3 and 4 the seam of loam only will be hewn out, so that it will not be mixed with the brown coal 75 when the latter is hewn down. When the part to be separately hewn runs obliquely, the slide 10 and the carriages 1 and 2 are moved simultaneously in the required directions. As the cutting tools rotate they can begin 80 and end the cut at any required position on the working face.

Fig. 3 shows a somewhat different arrangement of the upper carriage of the apparatus. In this case the upper carriage 35 carries on 85 its framing a circular segmental guide 36 for the upper end of the rigid guide-rail 9, the radius of which guide 36 is equal to the length of the link 6. This guide also allows, jointly with the link 6 a constrained parallel 90 guidance of the guide-rail 9.

Figs. 4, 5, 6, 7 and 8 show another modification of the invention. The special feature in this arrangement is that the carriages 1 and 2 are erected on special under-carriages 95 rotatable against the undersides of the carriage frames, so that the carriages can be taken around sharp curves in the rails 3 and 4.

The carriage 1 runs on two rails 3. On each rail run three bogie-frames 37, each 100 free to turn independently of the others. The middle bogie-frames are also movable to a slight extent at right angles to the direction of the rails. In this way the carriage 1 can be taken around very sharp curves as 105 shown in Fig. 6. In Figs. 7 and 8 it is seen that the carriage 2 is erected on two bogie-frames 38, which likewise enable it to pass sharp rail curves. The hewing apparatus is, by means of these turnable under carriages 110 37 and 38, in a position to hew down the working face at places where it has sharp corners and curves, without interruption or inconvenience.

In Fig. 9 is shown a shaft 39 turning in 115 bearings, which shaft is caused to rotate by any suitable means, not shown in the drawings. The shaft carries at its front end a disk 40 provided with cutters 41. In the drawing all the cutters are arranged in a circle near 120 the edge of the disk. They may, however, be distributed in various positions on the surface of the disk. This tool is specially suited for penetrating into the working face. It has the advantage that it operates always 125 with at least half of the cutters acting at one time as the slide moves along the rigid guide-rail 9. Several of the rotating cutter-disks 40 may be arranged side by side in the slide 10.

Fig. 11 shows a case wherein two cutter-disks 40 are present. There are also in the same figure two other cutter-disks shown in dotted lines, which cutter-disks can also be fitted to the same slide 10.

The apparatus may be so designed that two cutter-disks 40 always rotate in directions opposite to one another. The strain which the rotating disks exert upon the rope 10 by which the slide 10 is moved, depends for its direction upon the direction of rotation of the disks. If therefore, two disks, or other rotating cutter tools on the slide, rotate in opposite directions the strains exerted by the two tools act in opposition, and the rope is relieved from strain.

Figs. 12 and 13 show a special arrangement of the tool-slide. In this case the slide is divided into an upper part 42 and a lower part 43. The lower part 43 is adapted to rotate on the upper part 42, and can be clamped thereto in any required position. Fig. 13 shows a position of the lower part 43 in which the cutter-chain 19 runs parallel to the rigid guide-rail 9, while in dotted lines is shown a position of the lower part 43 in which the cutter-chain 19 runs at right angles to the rigid guide-rail 9. By turning the lower part 43 it is possible to suit the direction of motion and the width of cutter-tool to the direction in which the seams to be hewn down lie, and in which the tool is to be moved over the working face. The kind of rotating tool that is to be carried by the lower part 43 may be varied, for example, the two cutter-disks shown in full lines in Fig. 11, may be arranged on the lower part 43. According to the position of the lower part 43 a broader or a narrower strip of the working face can be hewn down.

In Fig. 14 is shown a hewing apparatus in which the forward movement of the tool toward the working face is effected in a manner different from that employed in the apparatuses shown in Figs. 1 and 4. In this case there is fitted to the carriage 1 a rigid guide-rail 44, fixed permanently to the framing of the carriage 1, and is not supported by a second or upper carriage. That, however, is not the essential feature of this form of hewing apparatus, as the guide-rail 44 may without departing from the nature of the invention, be connected flexibly to the carriage 1 and be supported by an upper carriage. The slide 45, movable on the rigid guide-rail carries a rotating cutting tool 46 which is driven by any suitable motor. This tool is movable on the slide in the direction of the shaft 47, so that it can be moved forward toward the working face while the rigid guide-rail remains stationary. A similar construction of the slide is shown in Figs. 15 and 16. The slide 45 carries, in this case, a movable part 48 on which the cutter-roller 49 is journaled. This cutter-roller is rotated by means of an

electric motor 50, with the help of a train of gearing 51, the chain 52 and the sprocket wheels 53 and 54. By moving the part 48 on the slide 45 the cutter-roller can be moved toward and away from the rigid guide-rail 44.

With the apparatuses shown in Figs. 14, 15 and 16 the hewing down of the working face is carried out in the same way as with the apparatus shown in Fig. 1. Only at the parts where, in the apparatus shown in Fig. 1, the rigid guide-rail 9 is raised and lowered by means of the tackles 11 and 12 the cutting tool 46, or the cutter-roller 49 is moved forward or backward. This apparatus has the advantage of greater simplicity, not only in the construction but in the manipulation, for it is not necessary to move the heavy guide-rail 9 every time for producing the forward movement.

Numerous modifications may be made in the apparatuses described without departing from the scope of the invention. It is especially indifferent what kind of rotating cutting tool is employed in the slide. As the drawings show it may be a cutter-disk, a cutter-chain, or a cutter-roller, and yet other forms may be used. It is also unimportant in what way the frame of the hewing apparatus is constructed. The constructions shown are only given by way of example.

I claim:

1. An apparatus for hewing minerals in open workings, comprising a rigid guide rail, a slide movably supported and guided on said rail, a rotating cutting tool carried by said slide, and independent means for supporting and adjusting the upper and lower ends of the guide rail.

2. An apparatus for hewing minerals in open workings comprising a rigid guide rail, a slide movably supported and guided on said rail, a rotating cutting tool carried by said slide, independent means for supporting and adjusting the upper and lower ends of the guide rail, and means for constraining the guide rail to move parallel to itself.

3. Apparatus for hewing minerals in open workings in which a bucket-chain is combined with the lower end of the rigid guide-rail for the tool-slide.

4. An apparatus for hewing minerals in open workings having a bucket-chain connected with the lower end of a rigid guide-rail for a tool-slide, in which the connecting links for the movement of the rigid guide-rail are so arranged that the deepest position is reached when the guide-rail has completed its forward movement.

5. Apparatus for hewing minerals in open workings having a bucket-chain connected with the lower end of a rigid guide-rail for a tool-slide, in which the lower connecting link of the rigid guide-rail serves at the same time as a bucket-guide for a part of the bucket-chain.

6. Apparatus for hewing minerals in open workings in which the carriages carrying the rigid guide-rail of the tool-slide are mounted upon rotatable under carriages.
- 5 7. A tool-slide for hewing apparatus with several rotating cutter-tools two of which rotate in opposite directions to one another.
8. A tool-slide for hewing apparatus which consists of an upper part having a lower part
10 arranged rotatably and adjustably thereon, which lower part carries a rotating cutting-tool.
9. Apparatus for hewing minerals in open workings having a tool-slide moving on a rigid guide-rail and carrying a rotating cutting-tool which can be fed forward from the slide. 15

In witness whereof I have hereunto set my hand in presence of two witnesses.

EMIL WISCHOW.
